UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,318,617.

Specification of Letters Patent.

Patented Oct. 14, 1919.

Application filed May 4, 1917. Serial No. 166,377.

To all whom it may concern:

Be it known that I, WILLIAM A. SMITH, a citizen of the United States, residing at Denver, in the county of Denver and State of Colorado, have invented certain new and useful Improvements in Rock-Drills, of which the following is a specification.

The present invention in its preferred embodiment relates to rock drills of the hammer type, and one of the primary objects is to provide a novel and simple combination of great effectiveness, including a hammer piston that can be reversed, so that either end may be utilized for delivering the blow, and at the same time so construct said piston and parts associated therewith that cleansing fluid can be delivered to the drill bit, irrespective of the reversal of the piston.

A further and important object is to provide motive fluid actuating means of an effective character for rotating the drill bit and to utilize the exhaust therefrom for hole cleansing purposes.

Still another and important object is to provide novel, effective and convenient means for controlling the operation of the mechanism.

The preferred embodiment of the invention is illustrated in the accompanying drawings, wherein:—

Figure 1 is a plan view of the drill.

Fig. 2 is a longitudinal sectional view therethrough.

Fig. 3 is a rear elevation with one of the hand grips in section.

Fig. 4 is a detail side elevation of the rear head and associated parts.

Fig. 5 is a cross sectional view through the drill rotating motor.

Fig. 6 is a detail sectional view of the exhaust controlling valve.

Similar reference numerals designate corresponding parts in all the figures of the drawings.

In the embodiment illustrated, a drill actuating motor is employed, comprising a cylinder member, which consists of a body 7, a rear head 8, and a front head 9. The front and rear heads are connected by side bolts 10. The body 7 is provided with a piston head chamber 11 and the rear head 8 has a neck chamber 12 communicating with the rear end of the chamber 11, and having an enlarged rear portion 13. The front end 55 of the body 7 is provided with a reduced

portion 14, in which is formed a forwardly extending neck chamber 15 that communicates with the front end of the chamber 11, said neck chamber 15 having an open front end.

Operating in the cylinder member is a piston, comprising a central head 16 that reciprocates in the head chamber 11, said head being provided with integral oppositely extending necks 17 and 18, these necks being duplicates one of the other, and operating respectively in the neck chambers 12 and 15. The neck 17 is provided contiguous to the head 16 with a reduced portion forming an annular channel 19, while the neck 18 has a corresponding portion or channel 20. The enlarged rear end of the neck 17, it will be noted, is movable into the enlarged portion 13 of the neck chamber 12, while the front end of the front neck 18 is adapted to pass beyond the reduced portion 14, in which the neck chamber 15 is located.

Motive fluid, preferably air, is supplied to the machine through a nipple 21 shown in Fig. 1, which nipple communicates with a chamber 22 formed in the upper portion of the rear head. Located at the inner end of the chamber is a tapered valve seat 23, in which is rotatably mounted a tapered valve 24 having an exposed stem 25. This valve is provided with a longitudinal channel 26 communicating with the chamber 22, and said channel has a lateral port 27 that is movable into and out of communication with a passageway 28 formed longitudinally in the rear head 8 and the body 7. The passageway has a lateral port 29 communicating with the enlarged portion 13 of the neck chamber 12. Another lateral port 30 opens into an annular groove 31 formed in the front portion of the neck chamber 12. A third port 32 opens into an annular groove 33 formed in the rear portion of the front neck chamber 15.

It will be evident that when motive fluid is admitted to the passageway 28, by turning the throttle valve 24 so that the port 27 will register with said passageway, motive fluid will be constantly in the rear enlarged portion 13 of the neck chamber 12, and will also enter the grooves 31 and 33 with the hammer piston in the position illustrated in Fig. 2. This motive fluid will find its way from the groove 33 into the head chamber 11 in advance of the piston head 16 because of

the position of the channel 20, whereas the fluid from the groove 31 will be cut off from admission to the rear of the head 16. The portion of the head chamber 11 in rear of said head is, however, open to the atmosphere through an exhaust port 34. As a consequence, the motive fluid acting against the front face of the head 16 will drive the piston rearwardly until the front portion 10 of the groove or channel 20 is cut off from the groove 33. The rearward movement of the piston will of course carry the groove or channel 19 of the rear neck 17 to a position where it will afford communication between the groove 31 and the rear end of the head chamber 16, whereupon motive fluid will operate against the rear face of the piston head 16 and drive the piston forwardly. When in this position, the exhaust port 34 20 is in communication with the front portion of the head chamber 11 in advance of the head 16.

The front head 9 is extended to form an internal chamber 35 in which is rotatably mounted a chuck 36 having an angular socket 37 adapted to receive the drill steel or bit 38, so that while the said steel or bit can be readily detached, it is rotatable with said chuck, and is furthermore in a position 30 to be struck by the front end of the hammer piston. The rear portion of the chuck 36 is provided with an integral worm gear 39, with which meshes a worm 40 formed on a shaft 41 of a turbine piston. This turbine 35 piston preferably comprises a pair of intermeshing wheels 42 located in a case 43 formed upon one side of the front head 9, and including a removable cover or head 44. One of the wheels 42 has keyed to it, 40 as illustrated at 45, the shaft 41, said shaft being provided with suitable roller bearings 46 and a step bearing 47. The other wheel is mounted on roller bearings 48.

Motive fluid from the supply chamber 45 22 is delivered to the turbine by means of a passageway 49, which may have a dust strainer 50 placed therein. The passageway 49 is connected to the chamber 22 by a valve seat 51 in which is rotatably mounted 50 a valve 52 having a longitudinal bore 53 provided with oppositely extending ports 54 and 55. The port 54 is in constant communication with the chamber 22, while the port 55 is movable into and out of communication with 55 the inlet end of the passageway 49. The valve 52 is provided with an exposed actuating stem 56. It will be noted by reference to Fig. 1 that the valve 52 is disposed longitudinally of the apparatus, while the valve 60 56 is arranged at right angles thereto.

Carried by the rear end of the apparatus is a frame 57 carrying a transverse handle 58, which includes a pair of hand grips 59 and 60, the latter being rotatably mounted 65 on a transverse bolt 61. The hand grip 59

has an internal sleeve 62 journaled on a wear and spacing sleeve 63, and carried by said grip is a crank arm 64 having an offset pin 65 engaged in a slot 66 formed in a crank arm 67 that is clamped as illustrated at 68 70 upon the projecting stem 25 of the throttle valve 24. The other hand grip 60, constructed similarly to 59, has a crank arm 69 to which is pivoted a link 70 shown in Figs. 3 and 4. This link 70 is also pivotally 75 connected to a crank arm 71 affixed to the projecting stem 56 of the valve 52. It will thus be evident that an operator grasping the handle of the machine cannot only hold it to its work and direct it as desired, but 80 by turning the grips, can independently control the supply of motive fluid to the drill actuating motor, and also to the drill rotating motor.

For the purpose of supplying cleansing 85 fluid to the drill bit, a tube 72 is employed that is suitably clamped, as illustrated at 73, in the rear wall of the rear head 8. Any suitable means are provided for supplying liquid to this tube through ports 74. The tube, as shown, extends axially through the neck chamber 12, the head chamber 11 and the neck chamber 15, and preferably is of sufficient length to enter the bore 75 of the drill bit. To effectively support the tube 72, and at the same time prevent danger of its being jammed, the hammer piston is provided with a central bore through which said tube passes. The end portions 76 of this bore are of greater diameter than the tube, so that said tube is spaced from the walls thereof, while the central portion or substantially that defined by the head 16, is of less diameter, as shown at 77, forming a sliding fit for the tube. With this arrangement therefore it will be evident that 100 cleansing liquid is directed through the motor to the drill bit and is carried by the latter to the bottom of the drill holes.

It is also desirable that gaseous fluid be 110 employed for clearing out the cuttings, and in the present embodiment, the exhaust from the drill rotating motor is employed for this purpose. This exhaust is conducted by a passageway 78 from the rotary motor or 115 turbine into a chamber 79 formed for the purpose in the rear portion of the chuck 36, and as the rear end of the drill bit is in this chamber, it will be readily apparent that the exhaust has access to the bore 75. 120 However, inasmuch as under some conditions there is an oversupply of this exhaust, another passageway 80 leads from the chamber 79 to a valve casing 81 formed upon one side of the body 7. In this valve casing, as illustrated more particularly in Fig. 6, is a rotary exhaust controlling valve 82 having a central bore 83 opening to the atmosphere, and a lateral port 84 that is 125 movable into and out of communication with 130

the passageway 80. The valve 82 has a suitable operating handle 85. By turning this valve to the desired position, the amount of exhaust delivered through the drill bit 5 can be varied.

For the purpose of lubricating the apparatus, a lubricant reservoir 86 is formed in the rear head 8 and is supplied through a port closed by a removable plug 87. Disposed alongside the reservoir 86 is a chamber 88 containing a wick 89, and said chamber 88 has communication by means of a port 90 with the reservoir 86, and also is in communication with the supply chamber 15 22 through a port 91, shown in Fig. 1.

From the foregoing, it is thought that the construction, operation and many advantages of the herein-described invention will be apparent to those skilled in the art, without further description, and it will be understood that various changes in the size, shape, proportion and minor details of construction, may be resorted to without departing from the spirit or scope of the invention. 25

Having thus fully described my invention, what I claim as new, and desire to secure by Letters Patent, is:—

1. In apparatus of the character set forth, the combination with a cylinder member, of 30 a piston operating therein and comprising a head having oppositely extending necks, means controlled by external portions of the respective necks for supplying motive fluid alternately to opposite faces of the head to 35 actuate the piston, said necks and head having alined bores of different diameters longitudinally therethrough, and a fluid conducting tube passing through the piston and being free from the walls of the bore of 40 greater diameter but engaged with the walls of the bore of less diameter.

2. In apparatus of the character set forth, the combination with a cylinder member 45 having a piston head chamber and elongated neck chambers extending from opposite ends thereof, of a piston having a head in the head chamber and oppositely extending elongated necks in the neck chambers, said 50 piston having a bore extending axially through the head and both necks and opening at the outer ends of the latter, a tool holder at one end of one neck chamber and a cleansing fluid conducting tube mounted 55 at the opposite end of the other neck chamber, said tube extending axially of said neck and head chambers for delivering cleansing fluid to a drill bit placed in the tool holder, the piston being reversible to permit either 60 neck to be utilized for delivering the blows and the axial bore and tube permitting such reversal and providing for the delivery of the cleansing fluid irrespective of which neck is foremost, and ports covered and uncoved 65 ed by the piston irrespective of its reversal

for delivering motive fluid to said piston to actuate the same.

3. In drilling apparatus, the combination with a cylinder member having a head chamber and oppositely extending neck 70 chambers, of a reversible hammer piston having a head operating in the head chamber and oppositely extending necks respectively operating in the neck chambers, either neck being operable in either neck 75 chamber accordingly as the hammer piston is reversed, means controlled by external portions of the necks for supplying fluid alternately to opposite sides of the head, said necks and head having alined bores there- 80 through independent of the fluid supplying means to the head, and a fluid conducting tube carried by the cylinder member and extending through the bores of the rear neck and the head, said tube permitting the reversal of the hammer piston and co-operating therewith when either neck is rearwardly. 85

4. In drilling apparatus, the combination with a drill actuating motor and a drill rotating motor, of handle means for holding 90 the apparatus to its work—said handle means being movably mounted thereon, means for supplying motive fluid to the motors, and valve mechanisms for independently controlling the fluid supply to the 95 motors, said handle means being connected to said valve mechanisms for operating the same.

5. In drilling apparatus, the combination with a drill actuating motor and a drill rotating motor, of handle means for holding 100 the apparatus to its work including relatively movable hand grips, means for supplying motive fluid to the motors, and valve mechanisms for independently controlling 105 the supply to the motors and respectively operated by the hand grips.

6. In combination with a drill actuating motor, of a rotatable chuck, a drill rotating motor, a handle frame, hand grips rotatably 110 mounted on the frame, means for supplying motive fluid to the motors, valves mounted on the motor, said valves serving to control the flow of actuating fluid to the drill-rotating and drill-actuating motor respectively, 115 means connecting the hand grips and valves for controlling the movement of the valves independently, and means associated with the drill rotating motor for rotating the chuck. 120

7. In drilling apparatus, the combination with a drill actuating motor and a drill rotating motor, of a fluid supply receiving chamber, passageways for conducting fluid from the chamber to the respective motors, 125 angularly disposed valves for respectively controlling the passage of fluid through the passageways, and alined actuating devices for the valves.

8. In drilling apparatus, the combination 130

- with a drill actuating motor and a drill rotating motor, of a fluid supply receiving chamber, passageways for conducting fluid from the chamber to the respective motors, 5 a valve extending across the chamber for controlling the motive fluid supply therefrom to one motor, and a second valve having communication with the chamber for controlling the motive fluid supply to the other motor.
10. In drilling apparatus, the combination with a drill actuating motor and a drill rotating motor, of a transversely disposed handle for holding the apparatus to its work, including a plurality of movable hand grips, means for supplying motive fluid to the motors, and valve mechanism controlling the motive fluid supply connected to and operated by the hand grips.
15. In drilling apparatus, the combination with a drill actuating motor and a drill rotating motor, of a transversely disposed handle for holding the apparatus to its work including spaced rotatable hand grips, 20 means for supplying motive fluid to the motors, valves for respectively controlling the motive fluid supply to the motors, and connections between the valves and hand grips for causing their respective operations on the rotation of said hand grips.
25. In apparatus of the character set forth, the combination with a drill actuating motor, comprising a cylinder member and a reversible hammer piston therein comprising a head having oppositely extending reduced necks, of a cleansing fluid conducting tube projecting into the hammer piston, said piston head and necks having alined longitudinal bores therethrough that permit the reversal of the piston, with the consequent utilization of either neck as the blow delivery end and the introduction of the tube into the opposite neck, and ports covered and uncovered by the piston irrespective of its reversal for delivering motive fluid to said piston to actuate the same.
30. In apparatus of the character set forth, the combination with a drill actuating motor comprising a cylinder member and a
- reversible hammer piston therein comprising a head having oppositely extending reduced necks, of means controlled by the necks for respectively delivering motive fluid against opposite sides of the head, a chuck for receiving a drill bit having a bore therethrough, a cleansing fluid directing tube mounted at the rear end of the cylinder member and having a delivery end adapted to discharge fluid into the bore of said drill bit, said piston head and necks having alined longitudinal bores therethrough to receive the tube, said necks and bores permitting the reversal of the piston and the consequent utilization of either end as the blow delivery end, while properly controlling the actuating fluid, and furthermore permitting the tube to be entered in either end when so reversed.
35. In apparatus of the character set forth, the combination with a barrel having a reduced extension, of a hammer piston mounted in the barrel and operating in said extension, a front head for the barrel, a rotatable chuck in the front head having a sleeve portion, the rear end of which overlaps the barrel extension, and means for delivering cleansing fluid between the sleeve and extension to a drill bit placed in the chuck.
40. The combination with a barrel having a reduced extension, of a hammer piston mounted in the barrel and operating in said extension, a front head for the barrel, a rotatable chuck in the front head having a sleeve portion surrounding and spaced from the extension, a drill rotating motor mounted on the barrel, gearing for rotating the chuck from the motor, means for supplying motive fluid to the motor, and means for directing the exhaust from said motor to the space between the reduced extension and the sleeve.
45. In testimony whereof I affix my signature in the presence of two witnesses.
